UNITED STATES PATENT OFFICE

WILLIAM D. JOHNSON, OF MILLER, SOUTH DAKOTA

CLOCK

Application filed May 11, 1929. Serial No. 362,392.

My invention relates to clocks of the type embodying both a time mechanism and an alarm mechanism, and the primary object of the invention is to simplify this type of clock by employing a single main spring adapted to drive both the time and the alarm mechanisms.

Another object of my invention is to adapt the common types of time pieces to the invention with a minimum amount of change in the present design and construction of such time pieces.

My invention is particularly valuable in connection with the ordinary low-priced alarm clock where the elimination of even a small part is a matter of great importance.

Another basic object of my invention is to provide an arrangement wherein both the time and alarm mechanisms are driven from a single spring, (as compared with the driving of each of the mechanisms by an individual spring) without any corresponding division of the power applied to the individual mechanisms. That is, I contemplate the use of a single spring of the same power as the old spring, and to apply the same amount of power to both of these mechanisms with the single spring as was previously applied with individual springs.

In reference to the last object, the method of accomplishment may be stated at this point without referring to the detailed description of a mechanism involving my invention. If it were attempted to drive both alarm and time mechanisms from one end of the spring and to secure the other end to a fixed part of the clock frame, the power would be divided between the two mechanisms. My invention contemplates driving one of the mechanisms from one end of the spring and the other mechanism from the other end of the spring. Thus the power which would be uselessly applied to a fixed part of the clock frame in a case where one end of the spring were fixed is employed in driving one of the mechanisms. This follows from the fact that for every force, there must be an opposite and equal reactive force and my invention contemplates employing not only the normal uncoiling force of one end of the spring but also

the reactive force at the other end of the spring.

It will be understood that the double power attained from the spring will be offset partially by the fact that the spring will be unwinding more rapidly where it is driving two mechanisms from its respective ends than where one end is fixed. This can be compensated however, by an increase in the length of the spring, which need not be enough, however, to make the spring the full length of the combined springs of the present clock or may be allowed for by more frequent winding.

My invention has for a further object to arrange the mechanism.

With these and other objects in view, my invention consists in the construction, arrangement and combination of the various parts of my device, whereby the objects contemplated are attained, as hereinafter more fully set forth, pointed out in my claim, and illustrated in the accompanying drawings, in which:

Fig. 1 is a plan view of a common type of alarm clock with one of the frame plates removed, embodying my invention.

Fig. 2 is a sectional view taken on the line 2-2 of Fig. 1.

Fig. 3 is a detail, sectional view taken through the axis of the main spring assembly.

Fig. 4 is a detail view of the ratchet assembly.

Fig. 5 is a detail, sectional view of a modified form of the spring assembly showing the ratchet.

Fig. 6 is a plan view of the same.

Fig. 7 is a detail, sectional view of a further modified form of the main spring assembly showing another ratchet mechanism embodied therein.

Fig. 8 is a plan view of the same.

Fig. 9 shows a further modified form of the invention.

Fig. 10 illustrates how the invention can be further modified and

Fig. 11 is a view of a further modification of the invention.

The clock shown in Figs. 1-4, inclusive, is modeled after the Westclox "sleep-meter".

In the present construction this clock includes the frame plates 10 and 11, connected by posts 12 and the alarm mechanism A and time governor mechanism B, respectively.

5 The alarm mechanism A in this clock is in the form of a clapper, adapted to engage a bell carried by the casing of the clock (not shown).

10 The main spring 13 is secured at one end to a barrel 14, in which it is enclosed, and at its other end to a main spring staff 15, which carries a drive gear 16. The winding of the spring is accomplished by rotating the key 17, which transmits winding power to the 15 barrel 14 through the medium of the key shaft 18 threaded at 19 into the hub 20 of the barrel 14. The hub is secured rigidly to the barrel.

15 In the present type of clock, the barrel 20 is held against retrograde movement by a ratchet acting between the hub 20 and the frame plate 11. The energy stored in the spring must then find its outlet through the gear 16 and the train of gears 17a, 18a, 19a, 25 20a, 21, 22 and 23 to the governor escapement B. This part of the construction is unchanged in the preferred form of my invention with the exception that the ratchet between the hub 20 and the plate 11 is removed 30 so as to allow the barrel to turn freely in either direction.

25 A gear 24 is secured to the barrel and drives the alarm device A through the medium of the train of gears 25, 26, 27 (shown in dotted lines) the scape wheel 28 and the double ended pawl 29, which carries the device A.

35 It will now be seen that one end of the spring applies power to the alarm mechanism A through the medium of the barrel, the drive gear 24 and the train of gears 25-27 while the other end of the spring applies power to the governor mechanism B through the drive gear 16 and the train of gears 17a-23. Each of the driven mechanism constitutes an anchor for the end of the spring opposite the end which drives the other driven mechanism.

40 In order to rewind the spring, it is necessary that there be a ratchet connection somewhere between the alarm mechanism A and the governor mechanism B. This ratchet mechanism in the preferred form of the invention shown in Figs. 1-4 is embodied between the intermediate gears 25 and 26. The gear 25 is a pinion driven from the drive gear 24 and is mounted on a staff 30, which is provided with a collar 31, loosely supporting the gear 26; that is, the gear 26 is journaled 45 upon the staff 30. A ratchet wheel 32 is secured to the staff 30 and coacts with a pawl 33, carried by the gear 26. A common form of spring 34 is employed to urge the pawl into engagement with the ratchet wheel.

50 65 In other types of clocks, the winding shaft

extends clear through the spring and forms the driving gear staff. This type of construction is shown in Fig. 7, wherein the winding shaft 18 is provided with a threaded end 19, threaded into the driving gear staff 15a. In this form of construction, the spring is secured at its inner end to the staff 15a and at its outer end is normally secured to a post of the clock frame. In my invention this form of construction may be modified by securing the outer end of the spring to a barrel 14a, which is loosely mounted on the staff 15a as shown instead of being connected to the clock frame. The gear 24a is secured to the barrel 14a and the gear 16a is secured to the spring 13 at its inner end, a hub being provided on the gear 16a for this purpose. Instead of connecting the spring directly to the shaft, it is connected to the shaft through the medium of the ratchet device, which in this case comprises a ratchet wheel 32a, secured to the staff 15a and coacting with a pawl 33a, carried by the gear wheel 16a. A spring 34a engages the pawl 33a.

55 Fig. 5 shows another modification in which the winding power is applied to the barrel as in the preferred form of my invention. The ratchet device in this case, however, is located between the barrel and the drive gear 24b. It comprises an internal ratchet gear 32b, formed integrally with the gear 24b and a pawl 33b, carried by the barrel 14b and in engagement with the ratchet 32b. A spring 34b engages the pawl 33b. In this form of the invention, the gear 24b is loosely mounted 60 between the shoulder 40 of the barrel and a collar 41, secured to the barrel as shown.

65 The ratchet device may be interposed between the gear 16 and the governor mechanism B, as shown in Fig. 9, where the gear 16 is secured directly to the staff 15c, which in turn is secured to the spring 13. The other end of the spring 13 is secured to the barrel 14c, which is mounted loosely on the staff 15c. The driving gear 24 is secured to the barrel 14c. The ratchet device is shown embodied between the gears 17c and 18c. It will be understood that in the same way the ratchet device might be embodied between the gears 19a and 20a or 21 and 22 of the time 70 governor transmission.

75 The ratchet wheel in Fig. 9 is indicated by the reference character 32c, the pawl by the reference character 33c and the spring is indicated at 34c.

80 The gear 18c is mounted loosely on its staff 50 between the ratchet wheel 32c and a shoulder 51, formed on the staff.

85 It may be noted in connection with the form shown in Fig. 9, that it is applicable to the type of construction in which the spring is secured directly to the winding shaft.

90 The preferred form of the invention shown in Figs. 1-4, inclusive, may be modified by embodying the ratchet device in the 95

scape wheel 28. This form is shown in Fig. 10, in which the numeral 32d indicates the ratchet secured to the staff 52 of the scape wheel and in which the pawl is indicated 5 at 33d, secured to the scape wheel. The spring is shown at 34d.

The preferred form of the invention may also be modified by embodying the ratchet mechanism in the double ended pawl of the 10 alarm escapement. This modification is shown in Fig. 11 and instead of the double ended pawl of conventional design, I employ a double ended pawl having a body portion 53, a pair of pawls 54 and 55, respectively, hinged to the body member 53 and a pair of lugs 56 and 57, respectively, which limit movement of the pawls in one direction. The parts are so arranged that during winding movement, the scape wheel 20 28 may rotate past the pawls 54 and 55 in the direction which is opposite to its normal direction of rotation during operation of the alarm device, the pawls giving away under yielding movement of the spring 58 25 to allow the teeth of the scape wheel to pass.

In the forms shown in Figs. 10 and 11, it will be understood that the ratchet devices shown are merely substituted for the ratchet devices shown in Figs. 1-4, and the rest of 30 the mechanism will remain the same with the exception of the omission of the ratchet device, for which either of the modified forms is substituted.

It will now be seen that the essential features of my invention reside in the employment of a pair of driving gears, one for the alarm mechanism and the other for the time 35 governor mechanism, the use of a single spring, connected at its respective ends to the 40 two gears and adapted to drive them both simultaneously in opposite directions and the use of a ratchet device embodied at any place between the alarm device and the time governor.

45 The above elements constitute my invention in its broadest sense, although it will be understood that other features of my invention reside in the adaptation of this broad principle to the specific constructions of 50 common types of clock mechanisms in such a way as to embody a minimum amount of change in such mechanisms.

Some changes may be made in the construction and arrangement of the parts of my 55 invention without departing from the real spirit and purpose of my invention, and it is my intention to cover by my claim, any modified forms of structure or use of mechanical equivalents, which may be reasonably included within their scope.

I claim as my invention:

In a clock, an alarm mechanism, a time 60 governor mechanism, a main spring staff, a barrel coaxial therewith, said barrel comprising a spring retaining portion and a

semi-cylindrical portion of reduced diameter, a ring gear provided with external spur teeth and internal ratchet teeth rotatably mounted on the barrel and receiving said reduced barrel portion, a drive gear rotatably mounted on the shaft, a main spring secured at its inner end to the staff and at its outer end to the barrel, a winding shaft secured to the barrel, one of said mechanisms including a train of gears meshing with the ring and a pawl pivoted on the barrel within said ring gear and engaging said ratchet teeth thereof, the parts being so arranged that the pawl allows the barrel to rotate free from the ring gear in the direction of winding the spring.

Signed this 1st day of May, 1929, in the county of Hand and State of South Dakota.

WILLIAM D. JOHNSON.
